UNITED STATES PATENT OFFICE.

LAWRENCE W. LUellen, OF BOONTON, NEW JERSEY, ASSIGNOR TO INDIVIDUAL DRINKING CUP COMPANY, OF NEW YORK, N. Y., A CORPORATION OF MAINE.

CUP-CONTAINER.

1,256,913.

Specification of Letters Patent. Patented Feb. 19, 1918.

Application filed December 2, 1911. Serial No. 663,589.

To all whom it may concern:

Be it known that I, LAWRENCE W. LUellen, a citizen of the United States, residing at Boonton, in the county of Passaic 5 and State of New Jersey, have invented certain new and useful Improvements in Cup-Holders, of which the following is a full, clear, and exact specification.

This invention relates to cup holders and has for its object to provide an improved 10 device for supplying individual drinking cups. The improvement embodies a container or receptacle for storing a stack of nested cups and presenting these, one at 15 a time, in position for ready removal. The improvement also includes an organization which will enable the cup which is at the delivery position to act as a closure for the delivery opening. The cup-retaining devices will preferably be so situated that 20 the portions of the cup intended for receiving the contents and for the engagement of the mouth of the user will be shielded.

25 In the drawings accompanying and forming a part of this specification one practicable form of the invention is illustrated, wherein—

Figure 1 represents, partly in elevation 30 and partly in longitudinal section the improved cup holder containing a stack of nested cups.

Fig. 2 is an enlarged cross-sectional view.

Fig. 3 is a longitudinal section of Fig. 35 2; and

Fig. 4 is a longitudinal section of two cups nested together.

This invention is intended to store and hold ready for removal, one by one, a stack 40 of nested cups. These cups will be made of some suitable material, preferably waterproofed paper.

The cups may be waterproofed by paraffin, which will add a certain amount of stiffness to the cup as well as giving it a cleanly and pleasing appearance.

In Fig. 4 two of the cups are shown nested. It will be noted that the body portion 5, of the cup is made tapering and that the upper rim or drinking edge is provided 50 with an outwardly-disposed flange 6. The bottom 7, of the cup is located at an appreciable distance upwardly from the bottom-edge 8, of the side portion. This constitutes a flange so that when the cups are

nested this flange will act as a spacing projection for engaging the bottom 7, of the cup beneath it and spacing the side walls of the cups apart to prevent adherence one with the other, and also for spacing the 60 flanges apart so that these will engage individually the supporting devices later to be described. It will thus be seen that one cup will rest upon the cup beneath it and that the entire stack of cups in the nest will be 65 uniformly spaced.

A container or receptacle 10, will be provided for the stack of nested cups. In the present illustration this container is a glass tube for the purpose of displaying the cups. 70 The container is shown supported in a ring-shaped framework 11, which is somewhat in the nature of a bracket carried by a standard 12, which will be secured on some suitable support. The standard also carries a bracket 13, for embracing the container above the support 11, for affording additional security. A suitable frame 14, is provided at the top of the container to which a lid 15, is hinged, such lid being 80 provided with a locking catch 16. This will prevent removal of the cups from the top and will also prevent dust accumulating upon or in the upper cup of the stack.

In carrying out this invention it is intended that the cup will be yieldably supported in the container. The yieldability may be either in the cup itself or in the device which engages it, or both the cup and the engaging device may be yieldable, so 90 that upon force being exerted to remove the cup, yieldability of the support will be present and the cup will be removed without damage.

A plurality of elastically-yieldable abutments are illustrated for supporting the stack of nested cups. The abutment will engage the upper end or ends of one or more of the cups at the lower end of the stack and hold the lower cup in position for delivery 100 and also sustain the stack of cups. The abutment is shown as a movable shoulder and in the present illustration comprises a strip of spring metal bent into form and carried by a suitable support, in the present 105 illustration, a ring 11. Three of these abutments are illustrated. The form of each comprises a portion 17, secured to the ring 11, a portion 18, for supporting the lower 110 edge of the container 10, a resilient arm 19,

and an abutment or supporting portion 20 for engaging the cup. The cups will be supported directly by or upon the spring-pressed shoulders. In the illustration these 5 yielding seats engage the under-side of the flange of the lowermost cup.

From the foregoing it will be seen that the lowermost cup is supported in such position that it may be readily taken hold of, 10 and, by a downward movement, drawn through the supporting devices, either the cup or the supporting devices yielding, according to whichever of these is the weaker. It will also be seen that the lowest cup 15 constitutes a closure for the delivery orifice of the container.

Although but one form of my invention has been illustrated and described, it will be apparent that changes may be made 20 therein without departing from the spirit of the invention.

Having thus described my invention I claim:

1. A sanitary cup holder, comprising an 25 upright tubular cup receptacle having an open lower discharge end and one or more spring pressed cup supporting shoulders adapted to wholly support a stack of nestable cups therein in such manner that the 30 lowermost cup is held in a partially exposed position capable of being removed from its support independent of the others above it.

2. A sanitary cup holder, comprising a cup receptacle having an open lower delivery end and a plurality of spring pressed supporting cup abutments extending into the receptacle and adapted to wholly support a stack of nestable cups therein in such manner that the lowermost cup may be 40 detached independent of the others above it.

3. A sanitary cup holder, comprising a vertical open ended tubular cup receptacle, and one or more spring pressed members projecting into the receptacle and forming 45 yielding seats for removably supporting a plurality of nestable cups therein, in such manner that the lowermost cup protrudes below the receptacle in convenient position to be detached from its support.

50 4. A sanitary cup holder, comprising a

cup receptacle having an open lower discharge end, and adapted to receive a plurality of flanged nestable cups, and one or more spring pressed members projecting into the receptacle near its lower end and adapted to engage with the under side of the flange of the lowermost cup, whereby all of the cups may thereby be supported, with the lowermost one protruding so as to be in position for convenient removal. 60

5. A sanitary cup holder, comprising a tubular cup receptacle, and one or more spring pressed members projecting into the receptacle, and adapted to removably support a plurality of nested cups, that have 65 projections below their upper edges that are adapted to rest upon the cup next below, the lowermost cup being adapted to be removably supported directly upon the spring pressed members. 70

6. A sanitary cup holder, comprising a tubular open ended cup receptacle, a cover hinged to the upper end, a plurality of spring arms secured to the wall of the receptacle and having extension portions projecting into the receptacle, and adapted to removably support a plurality of nested cups in said receptacle, the lowermost one of which is directly carried by said extension portions in a partly exposed position 80 whereby it may be conveniently detached from its support. 75

7. A cup holder comprising a receptacle having an open lower end, a plurality of yieldable abutments projecting into the interior of the receptacle and forming yielding seats for removably supporting a stack of nested cups in such manner that the lowermost cup protrudes below the receptacle in convenient position to be detached 90 from its support and extend within the receptacle a sufficient distance to constitute a closure therefor. 85

In witness whereof I have hereunto set my hand in the presence of two subscribing 95 witnesses.

LAWRENCE W. LUellen.
